UNITED STATES PATENT OFFICE.

FREEMAN DAVIS AND LOYD DAVIS, OF CENTERVILLE, IOWA.

AMALGAMATOR.

Application filed January 17, 1927. Serial No. 161,618.

This invention relates to amalgamators for use in the dental profession, and aims to improve generally the construction of the amalgamator as shown in our Patent Number 1,608,583 granted November 30, 1926.

An important object of the invention is to provide means at the upper end of the body portion of the amalgamator for measuring the amounts of alloy and mercury to be dropped into the container of the amalgamator, thereby permitting the user to position material within the container with facility and with a degree of accuracy.

A further object of the invention is to provide a device of this character so constructed that the material held in the measuring portion of the device may be dropped into the rubber container forming a part of the invention, by the operation of a slide valve.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a side elevational view of an amalgamator constructed in accordance with the invention.

Figure 2 is a vertical sectional view through the amalgamator.

Figure 3 is a plan view thereof.

Figure 4 is a sectional view taken on line 4-4 of Figure 1.

Referring to the drawing in detail, the device includes a hollow body portion 5 formed with internal threads at the lower end thereof, which threads cooperate with threads of the removable bottom 6, forming a part of the body portion.

A circular flange 7 extends inwardly from the inner surface of the hollow body portion and is disposed adjacent to the upper end of the body portion as clearly shown by Figure 2 of the drawing, which flange forms a support for the rubber container indicated at 8, and which is suspended within the body portion, by the flange 9 resting on the flange 7, the flange 9 being formed integral at the upper end of the rubber container 8.

The body portion is formed with an up-

standing internally threaded flange 10 designed to receive the measuring member 11 which is also formed with threads. This measuring member is substantially funnel-shaped so that a quantity of alloy and mercury may be poured thereinto, and later deposited in the rubber container in a manner to be hereinafter more fully described.

Formed in the upstanding flange 10 is a cut out portion through which the slide valve 12 moves, the valve being constructed of thin sheet metal and provided with lateral offsets 13 to prevent the valve 12 from being pulled through the cut out portion, when the same is being operated to uncover the bottom of the member 11 to drop material into the container.

As clearly shown by Figure 2, this valve 12 slides over the upper edge of the rubber container and is forced into engagement with the rubber container by means of the measuring member 11, when the measuring member 11 is rotated in a clockwise direction to prepare the device for operation.

It will be seen that due to this construction, the valve 12 also provides a bottom for the measuring member, and when the proper quantity of material has been placed in the measuring member, and the measuring member slightly rotated, to disengage the valve 12, the valve may be withdrawn by the thumb and forefinger of the person using the device, whereupon the contents of the measuring device will drop into the rubber container 8.

The valve is now slid to its active position or a position as shown by Figure 4 of the drawing, whereupon the upper end of the rubber container is sealed and the amalgamating shaft may now be rotated to accomplish the purpose of the invention.

The amalgamator shaft is indicated by the reference character 14 and extends through the housing 15, the inner end thereof resting in an opening as at 16. The inner end of this shaft 14 is formed with an offset portion 17 on which the roller 18 is mounted, the offset portion of the shaft being such as to cause the roller 18 to contact with the lower tapered end of the container 8 throwing the material in the container, upwardly accomplishing the amalgamation thereof.

It might be further stated that the construction of the shaft and device is such that the device may be readily positioned over the usual dry shaft of a dental engine,

thereby eliminating the necessity of employing a separate form of engine for rotating the shaft.

We claim:

- 5 1. An amalgamator including a body portion, a container supported in the body portion, a removable measuring member supported on the upper end of the body portion, a valve disposed between the upper end of 10 the container and measuring member for controlling the passage of material to the container, and means for agitating the container to amalgamate the material contained therein.
- 15 2. An amalgamator including a body portion, a container in the body portion, a closure for closing the upper end of the body portion and container, said closure including an adjustable measuring member and a 20 slide valve member, said measuring member adapted to clamp the valve into close engagement with the container to close the container.
- 25 3. An amalgamator including a body portion, a container supported in the body portion, a measuring member rotatably mounted at the upper end of the body portion and having a funnel-shaped opening, a valve member above the container, said valve member adapted to uncover the bottom of the 30 measuring member to allow material to pass

into the container, and said valve member adapted to be clamped into engagement with the container by the measuring member to close the container.

4. An amalgamator including a body portion, a container supported in the body portion, means operating in the body portion for agitating the container, a valve for normally closing the upper end of the container, a measuring member above the valve and container, said valve providing a bottom for the measuring member, said measuring member adapted to normally hold the valve in its active position, and said valve adapted 45 to move to allow material to pass from the measuring member into the container.

5. An amalgamator including a body portion, a container in the body portion, a measuring member for directing material to the 50 container, a slide valve for normally closing the container and held in its closing position by the measuring member, and said valve adapted to move to its open position to allow material to pass from the measuring member into the container.

In testimony that we claim the foregoing as our own, we have hereto affixed our signatures.

FREEMAN DAVIS.
LOYD DAVIS.
